UNITED STATES PATENT OFFICE.

RALPH LOUIS SCHROEDER, OF OWENSBORO, KENTUCKY.

LIFE-SAVING BELT.

Application filed August 20, 1924. Serial No. 733,179.

To all whom it may concern:

Be it known that I, RALPH LOUIS SCHROEDER, a citizen of the United States, residing at Owensboro, in the county of 5 Daviess and State of Kentucky, have invented certain new and useful Improvements in Life-Saving Belts, of which the following is a specification.

This invention relates to an improved 10 device for swimmers' use, which may be conveniently referred to as a life saving belt.

The device is not to be confused with the commonly known water wings, floating tubes, and the like. These devices are worn 15 in an inflated condition. The present device, while simulating the common inflated tube, frequently seen, is worn in a normally deflated condition. The purpose of the device is to permit free swimming in any style; to make long distance and deep water swimming 20 perfectly safe, to establish the elements of confidence necessary to produce an expert swimmer; to lessen fear, and to eliminate drowning without the requiring of 25 physical exertion to render the device operative.

More specifically speaking, the improved belt comprises a fabric covered inflation tube, to be worn around the body beneath 30 the arm, and to be supported in this position by shoulder straps in a deflated condition to permit the free body movement required in swimming.

It is a feature of the invention to construct the belt of a diameter to permit of 35 full inflation of the device, in case of danger, without restricting the chest, inflation being compensated for by constructing the belt of a diameter to loosely surround the body, undue slapping and loose movement of the belt being eliminated by folding the same.

It is also an object to provide means for 40 automatically inflating the belt in case of danger, the means being such as to expand the tube to a predetermined degree to prevent possible bursting and to eliminate the aforesaid constriction of the body.

Other features and advantages will 45 become apparent from the following description.

In the drawing:

Figure 1 represents an elevational view 50 of the device inflated and placed in an operative position on a person's body.

Figure 2 is a top plan view of the device.

Figure 3 is an enlarged detail sectional view of a liquid air container used in conjunction with the device.

Referring to the drawings in detail, 1 60 represents an ordinary inflation tube, which in the present instance is provided with an elongated flexible filling tube 2. The rubber tube 1 is completely encased in a fabric cover 3 of a shape and size to permit the tube to be fully inflated. The belt is thus composed of the rubber tube and its casing. In accordance with the invention, the belt is of a considerably larger diameter 65 than the body, when it is in a deflated state. 70 The belt is so made as to permit free and unrestricted movement of the body in swimming, and as before stated, it is worn in a normally deflated condition. To prevent it from moving too loosely about the 75 body to interfere with free swimming, the fabric casing is provided with separable fasteners, disposed preferably at the front. While the fasteners could be of some other construction, they are preferably in the 80 form of snap fasteners 4. The complementary parts of the fasteners are arranged so as to permit portions of the belt to be folded, as indicated in Figure 2, and to permit the proper ones to be engaged for adjusting the belt to a comfortable size. Attached to the lower portion of the cover at the front are common garter clasps 5, which are adapted to be engaged with the bathing suit, as seen in Figure 1. These clasps act 85 in conjunction with a pair of shoulder straps 6 to maintain the belt well up under the arm. If desired, the rear ends of the shoulder straps may be stitched to the cover, with the forward end detachably connected 90 therewith, through the medium of additional separable snap fasteners 7.

As before indicated, a liquid air container or cartridge 8 is used, in conjunction with the device. The container is preferably 100 polygonal in shape, and is removably fitted in a similar shaped pocket 9 on the front of the cover. The pocket is constructed to facilitate insertion and removal of the container and is provided with lacing 10, to 105 maintain the container in place. As seen clearly in Figure 2, the container is provided with a filling and discharge neck 11 fashioned at its inner end to provide a valve seat 12. A hollow stem 13 is threaded into the neck 110

and has its inner end designed to form a valve 14 for coaction with the seat. The stem is provided with a small hand wheel 15 to rotate it for unseating the valve. The aforesaid air tube 2 is connected with this stem 13. The container is charged with liquid air, and is of a size compared with the belt to contain just enough of such air to completely inflate the tube, to guard against over inflation, and resultant discomfort or bursting.

In practice, the belt is applied as indicated in Figure 1, with the clasps hooked onto the bathing suit and the strap 6 passing forwardly over the shoulders and notched onto the belt. To facilitate swimming, the belt is normally deflated as indicated in Figure 2, and portions thereof folded upon themselves and held in such condition by the snap fastener provided.

Should the wearer encounter danger at any time, the small hand wheel 15 is turned to unseat the valve 14. Unseating of this valve permits the liquid air to gasify and flow into the tube 1 through the intake hose or tube 2. Thus, the rubber tube 1 is immediately inflated and during the period of inflation, the snap fasteners are automatically disengaged to permit full inflation.

A swimmer equipped with this belt will be perfectly safe to attempt distance swimming contests, to test his endurance, at considerable distances from the shore, knowing that when he is in danger, he can immediately inflate the belt to sustain himself indefinitely on the surface of the water. There are numerous other advantages for a belt of this kind, but these need not be enumerated.

I claim:

1. A life saving belt adapted to be worn normally in a deflated folded state, said belt comprising an inflation tube, a filling hose leading therefrom, a fabric cover in which said tube is encased; a pocket on said cover, a liquid air container arranged in said pocket, said hose being connected with said container, valved means controlling said container, shoulder straps attached to said cover, and coacting snap fasteners for adjusting the diameter of the belt. 50

2. A life saving belt of the kind specified adapted to be worn normally in a deflated condition, said belt being of a diameter to loosely surround the chest of the wearer, cooperating snap fasteners carried by the belt for permitting portions thereof to be folded upon said belt to permit the deflated belt to be adjusted to fit comfortably, said belt comprising an inflation tube, and a fabric cover therefor, said cover being provided with a pocket of polygonal cross section open at its outer end and provided with lacing for closing the open end, a liquid air container arranged in said pocket, said container being provided with a valve seat, a manually controlled valve cooperable with said seat, said liquid container being of a shape corresponding to that of the pocket to prevent rotation thereof in the pocket, a conducting hose leading from said container to said tube, and shoulder straps carried by said fabric cover for aiding in holding the belt in position. 60 65 70

In testimony whereof I affix my signature.

RALPH LOUIS SCHROEDER.
